UNITED STATES PATENT OFFICE.

JAMES H. WARD, OF CHICAGO, ILLINOIS.

DRUM.

Application filed April 9, 1923. Serial No. 630,975.

This invention relates to drums, particularly to snare drums, and has for its object the provision of means for holding and adjusting the snares of drums and the application of stress thereto directly across the head of the drum, in a substantially straight line,—without bending them near their ends into planes substantially at right angles to the head of the drum as customary,—thereby drawing the snares more intimately into contact with the center portion of the head with a minimum stress applied to them.

Another object is to provide improved means, secured to the shell of the drum, for tensioning and relaxing the snares.

A further object is to provide means for tensioning the snares, on one side of the drum and means, on the other side of the drum, to relax the snares, both means movable radially of the drum.

A further object of the invention is to remove the strain hoop from the path of the snares to permit its full inward movement and bridging the ends of the hoop by a member extending above the strain hoop to leave large unobstructed openings thru which the snares pass.

Other objects and advantages will readily appear to persons skilled in the art from a consideration of the following description, taken in conjunction with the drawings forming a part hereof, wherein:

Fig. 1 is a substantially central section thru a drum containing my invention.

Fig. 2 is an enlarged sectional view of the snare releasing device taken substantially on line 2—2 of Fig. 3.

Fig. 3 is a section taken on line 3—3 of Fig. 2.

Fig. 4 is a section of the snare tensioning device shown located on the opposite side of the drum head in Fig. 1.

In all the views the same reference characters are employed to indicate similar parts.

A drum embodying my invention is indicated by 5. 6 is the usual shell. 7 is the upper head. 8 is the lower head. 9 is the usual skin hoop of which there are two, one for each head. 10 is the usual strain hoop, of which there are two, one for each of the skin hoops. Means for drawing the strain hoops towards each other, for tensioning the drum heads, are not shown, as they are not of present interest. They may be of any of the known types.

Snares 11 extend diametrically across the

drum head 8 and terminates in substantially the same plane. They are tensioned by the device 12, shown in Fig. 4, located on one side of the drum and the snare releasing device 13 is for location on the opposite side of the drum. Each of these devices is secured to the shell 6 of the drum and they are movable radially of the drum to tighten or to loosen the snares 11.

The snare tensioning device 12 comprises a bracket 14 secured to the shell 6 by screws 15. It is provided with two outstanding spaced arms or standards 16, and two arms 17 at right angles thereto. Between the arms 16 a two arm lever 18, similar to the lever 18 shown in Figs. 2 and 3, is pivoted. The snare engaging ends of these arms 18 are each provided with a housing 19 having members 20, 21 and 22. The wall or member 22 of the housing comprising a plate is perforated to uniformly space the snares. A snare passes through each perforation.

Within the housing 19 of lever 18 is a snare clamping member 23 thru which screws 24 freely pass for threaded engagement with the cooperating threaded clamping member 23.

The arms 18 are perforated to receive a rotatably loose cross member 26, thru which a thumb screw 27 loosely passes into a similar cross member 28 threaded to receive the screw. The screw 27 carries a collar 29 secured thereto which abuts the cross member 26 when the screw 27 is turned to tighten the snares in a perfectly obvious manner.

Between the arms 16 is an internally threaded spacing sleeve 30 in both devices 12 and 13, which may be separable from or a part of the arms or standards 16, and those in the arms 18 are caused to register, whereupon the thumb screws 31 are inserted in the spacing sleeve, thus forming a pintle for the pivoted lever 18 and enabling the parts to be quickly disconnected, so that the tensioning and releasing devices together with the drum head and strain hoop may be removed from the drum and replaced without disturbing the adjustment of the snares.

When the screw 27 is rotated to tension the snares the engaging end of the lever 18 is moved radially of the drum and the tension is applied to the snares directly in line with their axes.

The device for quickly slackening the snares, shown in detail in Figs. 2 and 3, has the same sort of lever 18 pivoted to the stand-

ards 16 by screws 31 entering the spacing sleeve 30. The cross member 26 serves as a roller for the cam 32, and the flanges 33 serve as guides for the cam.

5 A cam lever 34, which may be an integral part of the cam 32 is pivoted to and between arms 17 at the base of the cam by pivot pin 35. The outward movement of lever 34 moves cam 32 from under roller 26 and releases the snares in a clearly obvious manner.

The housing 19 of the releasing device contains a series of aligning pins 36 grooved at their bottom ends to receive a snare 11. 15 The lower ends of the pins are internally threaded, each to receive a screw 37, each of which passes thru an elongated slot 38.

A screw 39 passes transversely thru each of the pins 36 to laterally move the respective pin in its slot, thereby to independently adjust each pair of snares. The pins are fixed in adjusted position by tightening the screws 37.

The strain hoop 10 is divided into two 25 equal parts leaving a large space 40 between adjacent ends shown as equal in height to the height of the hoop. A bridging member 41, substantially U-shape, having two legs 42, is secured to the adjacent 30 ends of the hoop parts, respectively.

The space 40 permits considerable latitude of movement of the strain hoop 10 in adjusting the position of the skin hoop 9 without disturbing the snares and, furthermore, the ends of the snares, with attached levers 18, may be passed thru the opening 40 in removing the snares and snare operating means entirely from the other parts of the drum.

40 While I have disclosed a single embodiment of the invention for clearness of description, it is manifest that considerable change may be made in the arrangement and configuration of the parts within the spirit and scope of the appended claims.

Having described my invention what I claim as new and desire to secure by Letters Patent, is:—

1. A drum having snares extending across 50 one head thereof; snare-engaging members secured to the shell of the drum; a two-part strain hoop, the ends of which are spaced apart adjacent the snares and a pair of U-shaped snare bridging plates, one at each 55 end of the snares, the major portion thereof extending above the hoop and having the ends thereof secured to adjacent ends of said hoop parts to join the hoop parts together and to provide openings for the 60 snares.

2. A drum having a shell; a head extending across each end of the shell; snares extending across one end of the drum and said head; a pivoted snare engaging means; a 65 cam lever for operating said means mov-

able substantially radially from the axis of the shell in a transverse plane with the axis of the shell to release the tension of the snares, and another snare-engaging means, on the opposite side of the drum, pivotally supported on the shell and movable substantially radially to vary the tension of the snares. 70

3. A snare drum having snares extending across the head of the drum and means, at 75 each end of the snares, pivotally supported on the shell, movable in substantially radial planes with respect to the axis of the drum to change the tension of the snares, a cam lever to move one snare engaging means. 80

4. A snare drum having snares extending across the head of the drum; a pair of pivoted snare-tensioning means, one on each side of the head, a cam lever movable in substantially radial planes with respect to the axis of the drum to vary the tension of the snares and means carried by one of said tensioning means to independently adjust 85 each pair of snares.

5. A snare drum having a two-part strain 90 hoop at one end thereof, the ends of said hoop members spaced apart to permit snares to pass between said ends and the hoop to be removed without disturbing the snares; bridging members joining the adjacent ends of the hoop and extending above the hoop; snares extending in a substantially transverse plane across the head of the drum, and members for tensioning said snares, pivotally secured to the respective sides of the shell of the drum and movable substantially radially of said shell, and a cam lever to move one of said snare engaging means. 95

6. In combination with a snare drum, a 100 snare tensioning device comprising a bracket secured to the shell of a drum; a cam lever substantially parallel with the axis of the drum pivoted at one end to the bracket, its other end having means for engaging snares of the drum and movable substantially radially of the drum and cam means pivoted on the bracket for moving the lever to tighten the snares. 105

7. In combination with a snare drum, a 110 snare tensioning device comprising a bracket secured to the shell of a drum; a cam lever, substantially parallel with the axis of the drum having one of its ends pivoted to the bracket, the free end movable substantially radially of the drum and having snare-engaging means; a cam pivoted on the bracket for moving said lever outwardly and another lever, integral with the cam, for moving the same. 115

8. A snare engaging lever, for tensioning 120 snares of a drum, having a three wall housing formed on one end thereof; means in the housing for independently adjusting each pair of snares, passing thru one wall; means to lock the snare adjusting means 125 130

passing thru another wall, the third wall being perforated, thru which perforations the snares pass to hold them uniformly separated.

- 5 9. A snare engaging lever for tensioning snares of a drum, having a three wall housing; a pin transversely movable therein to adjust the tension of the snares, there being one pin for each pair of snares; screws passing thru one wall, threaded thru the diam-

eter of the respective pins and passing thru a wall of the housing; screws threaded into the ends of the respective pins to lock them in adjusted position, and passing thru slots in another wall of the housing, the third wall being perforated to uniformly space the snares. 15

In testimony whereof I hereunto subscribe my name.

JAMES H. WARD.
